MECHANISM FOR APPLYING ROLLED SHEET MATERIAL TO VERTICAL SURFACES

Harold A. Herzog, Mercer Island, and Donald J. Gjesdahl, Seattle, Wash.

Application December 29, 1948, Serial No. 67,828

8 Claims. (Cl. 216—7)

1

Our invention relates to a mechanism for efficiently applying rolled sheet material to vertical surfaces. More particularly our invention relates to a mechanism for applying relatively heavy paper rapidly and efficiently to the walls of a shipping compartment, as in freight cars or ships, said paper being caused to extend close to the floor and around the corners, especially in preparing the car for shipping flour to avoid contamination of the same.

For purposes of definiteness and clearness of illustration, we will set forth our application as applied to the preparing of a shipping compartment, as in a freight car, truck or ship, in which sacked flour is to be transported.

While the optimum advantages of the mechanism embodying our invention may be obtained from its use in applying rolled sheet material to vertical surfaces, nevertheless it has its advantages in maneuvering a roll of relatively heavy sheet material while securing therefrom strips of sheet material to be applied to the floor or ceiling. The device is applicable to facilitating the lining of shipping compartments either from the size of relatively small containers to freight cars or compartments of a ship or truck. Furthermore, manifestly the device is well adapted to applying sheet material to the exterior of containers, the contents of which require special protection.

At the present time, a roll of heavy paper, some nine inches in diameter by sixty inches long, is manually moved about the car, while the paper is being unwound and secured to the wall of a car by appropriately located applications of glue. Such operation requires considerable time of two or more operators. Since the roll of paper may weigh one hundred pounds or more, it is obvious that such manual handling is tiring and results in inefficiency.

One of the problems presented is to have the paper or sheet material extend in close proximity to the floor of the car when secured in place. On one face of the machine, the paper must be free to move out to the wall and the castors supporting the base member must be of a size to permit easy rolling over relatively rough surfaces, that is, these considerations establish conflicting conditions, as the bottom edge of the paper must extend in close proximity to the floor while the proper size of the castors operates to require the base to be considerably above the floor. Also, it is a requirement that the device be constructed so that the paper may be applied in the corners of a shipping compartment. While

2

the roll of paper must be so mounted that it may be freely unwound, nevertheless friction on the edge of the sheet must be avoided. On the other hand, it must not be free to unwind faster than is desired.

A primary object of our invention is to provide a mechanism economical in manufacture and one characterized by the ease with which it may be conveniently and efficiently moved about so that the period of application of the paper to the surface for such papering is greatly reduced. Also, it is a primary object of our invention to provide an upper spindle of such construction which will permit of ready installation of the roll of sheet material in operative position within the mechanism. Further, an object of our invention is to provide a turntable mounting sufficiently close to the floor and this in conjunction with a yielding brake action that will provide an operative mechanism and will fully overcome said difficulties.

The above mentioned general objects of our invention, together with others inherent in the same, are attained by the mechanism illustrated in the following drawings, throughout which drawings like reference numerals indicate like parts:

Figure 1 is a front view in elevation of a mechanism which embodies our invention;

Fig. 2 is a view of the same in the direction of arrows on line 2—2 of Fig. 1;

Fig. 3 is a plan view of said mechanism;

Fig. 4 is a view of a base member of the same;

Fig. 5 is a view in perspective of a carriage for subtending the lower spindle as respects the base member 10;

Fig. 6 is a view of the top spindle in said mechanism for mounting a roll of paper; and

Fig. 7 is a view of the lower spindle in said mechanism for mounting a roll of paper.

On a base member 10 is mounted an upright frame 11 preferably formed of tubing welded together comprising upright tubes 12, 13, 14, 15 and 16 arranged in a triangular form having top links or members 17 and 18 forming legs of a triangle with the apex 19 and link or member 20 extending across the front to complete the triangle. The base member 10 is supported by castors 21.

On the one hand, it is important to have the castors of such size that they will permit rolling over relatively rough surfaces. At the same time, the roll 34 of paper must be capable of being run out on one side to be applied to a wall, and the paper must extend in close proximity to the floor

on said wall. To permit the castors to be of sufficient size and at the same time permit the paper to be secured on the wall in close proximity to the floor, the lower spindle must be located close to the plane of the bottom of the castors.

The mounting for the lower spindle (see Fig. 7) is carried on plate 22 carried below the base member or plate 10 by tubular frame means 23. The spindle 24 is located in opening 25 in plate 22 on which plate 22 is welded a ring 26 within which ring is disposed a ball bearing means having inner race 27 and outer race 28. Outer race 28 is held stationary in ring 26 by means of set screw 29. The spindle 24 is held integrally with inner race 27 and nut 30, by means of a lock washer 31 of standard construction. Nut 30 functions to clamp the parts together. Spindle 24 has flange 32 which rests on inner race 27. On this flange 32 is welded a turntable plate 33 on which a roll of paper 34 may be disposed by causing the upper portion of spindle 24 to protrude into the wooden bung 35 normally carried in the end portions of the roll of paper 34. It has been found highly important that the paper be mounted on a turntable so that the edges of the paper will not be subjected to friction of any consequence when the roll is being unwound.

A top spindle and its mounting is provided (see Fig. 6) as follows: A plate 36 secured in the front to frame member 20 and in the rear to frame member 37 has welded thereon a nut 38 having internal threads. A pin 39 extending through an opening 40 in plate 36 has secured on its upper end an enlarged threaded member 41, the threads of which engage the internal threads of nut 38. On the top of member 41 is secured a short bar 42.

Leg member 17 of the triangular frame (see Fig. 3) is longer than the other legs 18 and 20 of the triangle and is caused to serve as a vertical brush mounting member having vertical brush 43 which may press the paper 44 as it unrolls from the roll of paper 34 against the vertical wall 45. A resilient brake means for the roll of paper to prevent its unrolling except when desired is preferably provided by means of a diagonally disposed belt 46 having a spring mounting end member 47 secured to the upright member 12 of the frame 11, while the opposite end 48 of belt 46 may be fixedly secured to upright 16.

The mode of operation of the device embodying our invention is as follows: The upper spindle is unwound by means of bar 42 and removed from the nut 38 so that the lower end of the roll of paper 34 may have its wooden bung 35 placed over the tapering end of the lower spindle 24 and the end of the roll caused to rest upon the turntable 33. Then the top of the roll is moved inwardly so that the axis of the roll is in line with the opening 40 of plate 36. Thereupon, the pin 39 is caused to be moved downwardly into the bung 35a in the upper end portion of the roll of paper 34 by turning the bar 42 to thread member 41 in nut member 38.

Applications of glue are then placed on the vertical surface to be covered, and the paper 44 is then pulled out and placed against the glue and the machine is then caused to run with its front substantially parallel with the vertical surface with the brush 43 pressing the paper against the wall 45. In Fig. 3 the machine would be moving to the right of the drawing, i. e., in direction of arrow. When a corner of the shipping compartment is reached, it is manifest that the

machine can be turned on its axis with the brush member 43 on its extended arm 17 reaching into the corner of the compartment and pressing the paper into the corner itself. The paper is prevented from unrolling prematurely by means of the resilient brake means in the form of the belt 46 with its spring mounting 47—the opposite end 48 may be rigidly secured to its frame member as by riveting. The front of the machine is open from the bottom of the paper to its very top, the base plate 10 having an opening 49 on its front side so that the paper may run out freely over its entire width from the turntable plate 32 to the vertical surface being papered or covered. Having the lower spindle 24 suspendedly mounted, as respects base plate 10, provides for causing the paper to extend substantially to the floor.

The device provides a very efficient means for handling the relatively heavy roll of paper and permits the same to be unrolled in a manner for quick application of the paper to the vertical surfaces of a shipping compartment, whether it be in a freight car or in a ship or truck. Also, having the paper mounted in a mechanism of this character which permits it to be wheeled about and maintained in a position for unrolling the paper, relieves the operators of much manual effort—a one hundred pound weight not only being heavy in itself, but in the form of a sixty inch roll of paper is very inconvenient to handle. The paper in our invention is free to be unrolled when desired and at the same time the unrolling of the paper is definitely controlled by the resilient or yielding brake means 46 against prematurely unrolling. The providing of a vertical brush 43 outside of the perimeter of the frame provides a construction for very readily pressing the paper into the corners of a shipping compartment. Instead of brush 43, a roller may be substituted.

Obviously, changes may be made in the forms, dimensions, and arrangement of the parts of our invention, without departing from the principle thereof, the above setting forth only a preferred form of embodiment.

We claim:

1. A portable mechanism of the class described comprising a castor mounted base having an introverted side providing an opening for the out-feed of a web of sheet material; an upright frame carried by said base having an extension adjacent the opening of said introverted side; a sheet material guide carried by said extension; a sheet material roll mounting lower spindle carried by and below said base on a plane slightly above the bottom of the castors; and a sheet material roll mounting upper spindle carried by said frame, whereby a sheet of material may be fed out of said opening in the introverted side and over said guide which presses the said sheet against the wall and into corners thereof to which the sheet of material is to be applied.

2. A mechanism for applying rolled sheet material to vertical surfaces comprising a castor mounted base; an upright frame of general triangular form cross-sectionally considered carried by said base, said frame and base being open on one side opposite the apex of said triangle for the feeding out of sheet material of a roll of said material disposed in general in the boundaries of said triangle, the lateral side adjacent the opening of the triangle past which the sheet material is fed being extended as a brush mounting member; a vertically disposed brush carried

by said brush mounting member; a sheet material roll mounting lower spindle carried by and below said base; and a sheet material roll mounting upper spindle carried by said upright frame.

3. In a mechanism for applying rolled sheet material to vertical surfaces; a castor mounted base having an introverted side providing an opening for the outfeed of a web of sheet material, and a sheet material roll revolvably mounting spindle mounted below said base.

4. A mechanism for applying rolled sheet material to vertical surfaces comprising a castor mounted base; an upright frame of general triangle form cross-sectionally considered carried by said base; a sheet material roll mounting turn table carried by and below said base having a roll supporting face relatively close to the plane of the bottom of the castors irrespective of the diameter of the castors, whereby said sheet may be fed close to the base of the vertical surface; a sheet material roll mounting upper spindle carried by said upright frame; and a belt yieldingly held disposed spirally about a segment of the periphery of the roll of sheet material being fed.

5. A portable mechanism of the class described comprising an upright frame of general triangular form cross-sectionally considered having an open side; castors mounted on the bottom of said upright frame; an extension carried by said frame adjacent said open side; a sheet material guide mounted thereon; a sheet material roll mounting lower spindle carried by said frame; a plate carried by said frame; a nut secured to said plate; a sheet material roll mounting upper spindle comprising a pin having a bearing portion extendable within the end portion of said sheet material roll and having a threaded portion engageable with said nut, whereby said bearing is both supported and locked in position; and a belt yieldingly and contactingly extending about a portion of the roll of said sheet material on the side of said roll back of the open side of said frame, the ends of said belt being secured to said frame adjacent said open side.

6. In a mechanism of the class described, an upright frame of general triangular form cross-sectionally considered having a lower and upper sheet material roll mounting spindles and hav-

ing an open side; an extension means secured to and in line with the frame members forming one leg of said frame and disposed adjacent said open side; and a guide member carried by said extension, whereby the sheet material may be caused to pass over said guide while said material is being applied.

5 7. In a mechanism of the class described, an upright frame; an upright guide rigidly mounted on said frame; a base carried by said frame; a sheet material roll mounting lower spindle mounted on said base whereby a sheet of material may be fed over said guide from a roll of material mounted on said spindle, which guide presses the said sheet against the wall and into corners thereof to which the sheet of material is to be applied.

10 8. In a mechanism for applying rolled sheet material to vertical surfaces; an upright frame; a castor mounted base carried by said frame, said base having an introverted side providing an opening for the outfeed of a web of sheet material, an upright guide rigidly mounted on said frame adjacent one side of the opening of said 15 introverted side, the member of said base adjacent said opening and opposite to said guide having rounded corners whereby said base may operate as a guide while the device is being moved along a vertical wall.
